UNITED STATES PATENT OFFICE.

WILLIAM ROBERT YENDALL, JR., OF AURORA, ILLINOIS.

STOVE.

No. 899,936.

Specification of Letters Patent. Patented Sept. 29, 1908.

Application filed October 29, 1906. Serial No. 341,067.

To all whom it may concern:

Be it known that I, WILLIAM R. YENDALL, Jr., a citizen of the United States, residing at Aurora, in the county of Kane and State of Illinois, have invented certain new and useful Improvements in Stoves; and I do hereby declare the following to be a full, clear, and exact description of the invention, such as will enable others skilled in the art to which it appertains to make and use the same.

My invention relates to base-burner coal stoves and more particularly to new and useful improvements in air-circulating flues contained therein.

It has for its object to provide novel constructions of air-circulating flues, whereby the efficiency of the stove is greatly increased, by completely covering all interior or indirect radiating surfaces thereof, with circulating flues, by means of which currents of cool air are caused to circulate over said interior surfaces and thereby convert them into direct radiating surfaces.

My invention consists of further details of construction and the combination of parts as will be hereinafter described and more specifically claimed.

In the accompanying drawings, illustrating the preferred embodiment of my invention: Figure 1 is a side elevation of a stove constructed in accordance with my invention. Fig. 2 is a longitudinal vertical sectional view thereof. Fig. 3 is a vertical sectional view taken on line $x-x$ of Fig. 2 and looking in the direction of the arrow. Fig. 4 is a horizontal sectional view taken on line $y-y$ of Fig. 2. Fig. 5 is a similar view on line $z-z$ of Fig. 2. Fig. 6 is a sectional view on line $a-a$ of Fig. 3, and Fig. 7 is a similar view showing a modified construction of the finishing portion of the vertical air-flue.

While the drawings show the preferred embodiment of my invention, I reserve the right to make such changes in the construction shown and described as the scope of the claims hereunto appended will permit.

Referring more particularly to the drawings, the reference character 1 represents the bottom plate and 2 the top plate of the base of my stove. These two plates, together with the outside shell or casing 3, form a base-smoke flue 4. At the rear of the stove, and communicating with said base-flue there is arranged a descending smoke flue 5, communicating with the combustion chamber, and a return ascending smoke-flue 6 termi-

nating in the chimney opening 6^a. These vertical smoke-flues are formed by the main back or casing 7^a of the stove and curved flue strips 7 and 8. Said flue strips extend from their juncture 9 at the center of the main back or casing 7^a to the side casing or shell where the plate 9^a forming the rear surface of the ash-pit, fire-pot and combustion chamber joins said side casing. The space included between the said rear surface of the ash-pit, fire-pot and combustion chamber and the curved flue strips constitutes an air-circulating flue 10.

At the line of the smoke outlet or chimney opening 6^a the flue strips are brought forward as at 10^a to make room for a tea-kettle attachment 10^b, and the width of the air flue is also contracted making a narrow passage 10^c which after passing above the smoke-outlet widens out again and finally terminates in the pipe 11 to supply heated air to a room above. This leaves a passage 10^d on the left side of the stove for the products of combustion from the fire-pot to pass to the descending flue 5 and a passage 10^e on the right side which affords a seat for the direct draft damper 10^f. As the smoke-outlet is placed at the center of the main back, a strip 10^g is employed to carry the top of the ascending flue 6 past the center of the back so as to communicate with the smoke-outlet as shown in Fig. 6. In the modified construction the circulating flue 10 is carried in a direct line to the tea-kettle attachment. The chimney opening 6^a is then placed at the top of the ascending smoke-flue 6. By this construction, the circulating flue is only contracted sufficiently to make an opening for the direct draft damper 10^f and the passage 10^d as shown in Fig. 7.

A horizontal air-circulating flue 12 is formed between the top plate 2 of the base-flue 4 and the bottom plate 14 of the ash-pit. Openings 15 are formed in the casing or shell of the stove, said openings communicating directly with the air-circulating flue 12 for the ingress of air. As the bottom plate 14 of the ash-pit does not extend past the plate 9^a a passage 16 is left between said plate and the flue-strips 7 and 8 for the passage of air from the horizontal air-circulating flue 12 to the air-flue 10. The base-smoke flue 4 encircles a hollow flue strip 17 which is open at 18 for the ingress of air from the space below the base of the stove. The hollow flue strip 17 extends to the main back or casing

7^a. An opening 18^a is arranged in the plate 2, below the passage 16. This allows air to be taken from the floor of the room and fed to the vertical air-circulating flue 10. By 5 this arrangement of air-circulating flues, it will be seen that all plates that are heated by the products of combustion on one side are in direct contact with cool air on the other side or, in other words, I have eliminated 10 direct radiating surfaces and have converted them into direct radiating surfaces. It will be further noted that in accomplishing this result, the area of the smoke-flues has not been reduced, thereby retarding the draft as 15 in previous attempts to increase the radiating powers of heating stoves, and that the outside exposures or surfaces of the smoke-flues, which constitute direct radiating surfaces, have not been decreased. This was 20 25 the result when the said previous attempts were made by inclosing the ascending and descending smoke-flues in air-chambers, that is, valuable direct radiating surface was destroyed and the stove made cumbersome by the additional weight of material.

I claim:

1. A heating stove provided with a base-flue, descending and ascending flues, a horizontal air circulating flue and a vertical air-circulating flue formed entirely by interior plates of the stove, said vertical air-circulating flue communicating with said horizontal air-circulating flue, said air-circulating flues covering all interior smoke-flue surfaces.
2. A heating stove provided with a base-flue, descending and ascending flues communicating with said base-flue, continuous air-circulating flues covering all interior surfaces of said flues and the interior radiating 30 surfaces comprising the ash-pit, fire-pot and

combustion chamber, a hollow flue-strip arranged in said base-flue and extending to the extreme back of the stove, said flue-strip being open to the space below the base of the stove and having communication with said air-circulating flues, the casing of the stove between the base-flue and the bottom of the ash-pit being provided with openings therein having communication with said air-circulating flues. 45 50

3. A heating stove provided with a base-flue, descending and ascending flues, a horizontal air-circulating flue arranged between the said base-flue and the ash-pit, a vertical air-circulating flue arranged between the 55 interior plates of said descending and ascending flues and the rear plates of the ash-pit, fire-pot and combustion chamber, said vertical air-circulating flue having communication with the said horizontal air-circulating flue, a hollow flue-strip communicating with said vertical air-flue formed in said base-flue, the casing of the stove being provided with openings therein communicating with said horizontal air-flue for the purpose speci- 60 65 fied.

4. A heating stove provided with a wall forming the rear surface of the ash-pit, fire-pot and combustion chamber, and flue-strips forming the interior plates of a descending 70 and an ascending smoke-flue, said flue-strips extending from their juncture at the center of the main back to the side casing where said wall meets said side casing.

In testimony whereof, I affix my signature, in presence of two witnesses.

WILLIAM ROBERT YENDALL, JR.
